DESIGN FOR A BOTTLE

Marie Rose De Mascolo, Paris, France, assignor to Societe Anonyme Scherick, Paris, France, a corporation of France

Application July 19, 1935, Serial No. 57,746

Term of patent 14 years

To all whom it may concern:

Be it known that I, Marie Rose De Mascolo, a citizen of the Republic of France, residing at Paris, France, have invented a new, original, and ornamental Design for a Bottle, of which the following is a specification, reference being had to the accompanying drawing, forming a part thereof.

In the drawing

Fig. 1 is a side elevational view of a bottle showing my new design.

Fig. 2 is a fragmentary front view;
Fig. 3 is a fragmentary rear view; and
Fig. 4 is a top plan view thereof.

I claim:—

The ornamental design for a bottle, substantially as shown.

MARIE ROSE DE MASCOLO.
